UNITED STATES PATENT OFFICE.

JOHN LUKOWSKI, OF KENSINGTON, ILLINOIS.

DESIGN FOR A BRACELET.

41,779.

Specification for Design. Patented Sept. 19, 1911.

Application filed July 8, 1911. Serial No. 637,517. Term of patent 14 years.

To all whom it may concern:

Be it known that I, JOHN LUKOWSKI, a subject of the Emperor of Austria-Hungary, residing at Kensington, in the county of Cook and State of Illinois, have invented a certain new, original, and ornamental Design for a Bracelet, of which the following is the specification, reference being had to the accompanying drawing, forming a part thereof.

The figure is a plan of the bracelet, illustrating my new design.

I claim:—

The ornamental design for a bracelet, as shown.

JOHN LUKOWSKI.

Witnesses:

TOINRY RYBIAKI,
FELIKS. WALICRKI.
